US00D766244S

(12) **United States Design Patent** (10) **Patent No.:** **US D766,244 S**
(45) **Date of Patent:** **** Sep. 13, 2016**

(54) **SCANNER**

(71) Applicant: **Hand Held Products, Inc.**, Fort Mill, SC (US)

(72) Inventors: **Peng Zhou**, Suzhou (CN); **Yuefeng Mo**, Suzhou (CN); **Mark Lee Oberpriller**, Atlanta, GA (US); **Timothy R. Fitch**, Syracuse, NY (US); **Miansong Chen**, Suzhou (CN)

(73) Assignee: **Hand Held Products, Inc.**, Fort Mill, SC (US)

(**) Term: **14 Years**

(21) Appl. No.: **29/519,017**

(22) Filed: **Mar. 2, 2015**

Related U.S. Application Data

(63) Continuation of application No. 29/459,823, filed on Jul. 3, 2013, now Pat. No. Des. 723,560.
